TRANSMISSION FOR INVALID BEDS

Frank Gahm, Pasadena, Calif.

Application January 2, 1936, Serial No. 57,181

2 Claims. (Cl. 74—355)

This invention relates to invalid beds.

The general object of the invention is to provide an improved invalid bed and fracture frame which allows the patient to be placed in various positions so that the best opportunity for recovery may be provided.

A more specific object of the invention is to provide a fracture frame including novel means for adjusting the frame.

Another object of the invention is to provide a fracture frame including a roller mounted patient support wherein novel means is arranged for adjusting the support by turning the rollers.

Another object of the invention is to provide a patient turning device including a pair of rollers so mounted and arranged that the rollers may be turned independently or simultaneously to adjust the position of the patient.

Other objects and the advantages of this invention will be apparent from the following description taken in connection with the accompanying drawings, wherein:

Fig. 1 is a side elevation of a bed and fracture frame embodying the features of my invention;

Fig. 2 is a cross-section taken on line 2—2 of Fig. 1;

Fig. 3 is a transverse section taken on line 3—3 of Fig. 1;

Fig. 4 is an enlarged fragmentary section taken on line 4—4 of Fig. 1;

Fig. 5 is an enlarged fragmentary section taken on line 5—5 of Fig. 2;

Fig. 6 is an enlarged fragmentary section taken on line 6—6 of Fig. 3;

Fig. 7 is an enlarged fragmentary section showing the lifting mechanism taken on line 7—7 of Fig. 1;

Fig. 8 is a section of the lifting mechanism taken on line 8—8 of Fig. 7;

Fig. 9 is a section taken on line 9—9 of Fig. 7;

Fig. 10 is an enlarged fragmentary section taken on line 10—10 of Fig. 3;

Fig. 11 is a view similar to Fig. 10 showing the parts in another position;

Fig. 12 is an enlarged fragmentary section taken on line 12—12 of Fig. 3;

Fig. 13 is a section taken on line 13—13 of Fig. 10;

Fig. 14 is a section taken on line 14—14 of Fig. 13;

Fig. 15 is a section taken on line 15—15 of Fig. 2;

Fig. 16 is a side view of a traction device;

Fig. 17 is an enlarged section taken on line 17—17 of Fig. 16;

Fig. 18 is a central horizontal section through a modified form of canvas operating mechanism;

Fig. 19 is a section taken on line 19—19 of Fig. 18;

Fig. 19A is a fragmentary section taken on line 19A—19A, Fig. 19;

Fig. 20 is a section taken on line 20—20 of Fig. 18;

Fig. 21 is a fragmentary elevation looking towards the foot of the bed and with the canvas holding roller omitted;

Fig. 22 is a section taken on line 22—22 of Fig. 21;

Fig. 23 is a section taken on line 23—23 of Fig. 3; and

Fig. 24 is a section taken on line 24—24 of Fig. 1.

Referring to the drawings by reference characters I have shown my invention as embodied in a bed which is indicated generally at 10. As shown the bed includes a head 11 and a foot 12 with side rails 13 connecting the head and foot. This bed may be of any desired construction so long as it is sufficiently strong and of the proper size.

My fracture frame is indicated generally at A. This fracture frame includes a head portion 15 and a foot portion 16.

At the head the frame includes a hollow upright rectangular post 17 which is supported by a clamp member 18. As clearly shown in Fig. 4 the clamp member 18 is U-shaped with the post 17 positioned between the arms thereof. The clamp member 18 further includes a U bolt 19 which is positioned in suitable apertures in the member 18 and has a rod 20 positioned between the arms of the U bolt and one face of the clamp member. The U bolt 19 is provided with nuts 21 for clamping the member 18 to the post 17 and the member 18 to the rod 20. The rod 20 is secured to the side members of the head 11 of the bed as by welding.

Positioned in the post 17 I provide a rack bar 22 having gear teeth 23 thereon which are engaged by a gear 24 which is positioned in a housing 25 (see Figs. 7, 8 and 9) of an operating device 26.

The housing 25 is mounted on the post 17 and adjacent the gear 24 the housing and the post 17 have apertures 26' therein in which the gear 24 is positioned. The gear 24 is secured to a shaft 27 which is rotatably mounted in the housing 25 and has a worm gear 28 secured thereon. The worm gear 28 meshes with a worm pinion 29 which is secured to a shaft 30 which is rotatably

mounted in the housing 25. The shaft 30 extends each way from the housing 25 to adjacent each side of the bed where it includes a polygonal wrench or crank engaging portion 31. When the shaft 30 is rotated the gear 24 is rotated through the medium of the worm pinion 29, worm gear 28, and the shaft 27. When the gear 24 is rotated it moves the rack bar 22 either up or down depending on the direction in which it is rotated.

Rigidly mounted on the rack bar 22 by means of a stirrup 31' I provide a transverse bar 32, the ends of which have reduced bar portions 33 thereon.

15 Mounted on the bar 32 adjacent one side of the bed I provide an operating member 35 which is shown in detail in Figs. 10 to 14, inclusive. As shown the operating member 35 includes a casing 36 which includes an apertured boss 37 in which one of the reduced bar portions 33 of the bar 32 is positioned. The casing 36 is shown as secured in position on the portion 33 by a set screw 38. A shaft 39 is rotatably mounted in the casing 36 and the end thereof adjacent the side 20 of the bed includes a polygonal wrench or crank engaging portion 40. The opposite end of the shaft 39 is positioned in a sleeve 41 which is slotted at each end as indicated at 42. The shaft 39 has a key member 43 thereon which is positioned in one of the sleeve slots 42 to rotatably connect the shaft and sleeve. Slidably mounted on the shaft 39 within the casing 36 I provide a pair of spaced bevel gears 44 and 45 which are rotatably connected to the shaft by a spline 46 25 on the shaft. (See Fig. 12.) Positioned at a right angle to the shaft 39 and extending towards the foot of the bed the casing 36 has a shaft 47 rotatably mounted therein. Within the casing 36 the shaft 47 has a bevel gear 48 secured thereto which is positioned between the bevel gears 44 and 45. As shown in Fig. 10 the shaft 47 has an enlarged sleeve 49 thereon which is secured to the shaft by a pin 49' one end of which projects beyond the side of the sleeve. An 30 elongated hollow roller 50 is mounted on the sleeve 48 and adjacent one end has an enlarged recess 51 therein and a slot 52 opening into the recess. The roller 50 is positioned on the shaft 47 with the sleeve 49 positioned in one of the recesses 51 and with the pin 49' positioned in the slot 52. A piece of canvas 53 is shown as secured to the roller 50 by a plate 54 which is secured to the roller by screws 55, although other means for securing the canvas may be employed.

35 The canvas 53 is normally rolled around the roller 50 as shown in the drawings.

For shifting the gear 44 I provide a shifting member 56 which includes a flat horizontal plate 57 and a depending forked arm 58 the prongs 60 of which are positioned in a groove 59 provided in the hub of the gear 44. The plate portion 57 of the member 56 adjacent the end opposite the depending portion has an elongated slot 60 therein (see Fig. 14) and intermediate the slot 60 and the depending portion 58 the plate 57 has a threaded aperture 61 therein.

For shifting the gear 45 I provide a shifting member 62 which includes a flat horizontal plate 63 and a depending forked arm 64 the prongs of 70 which are positioned in a groove 65 provided in the hub of the gear 45. Adjacent the end opposite the prongs the plate portion 63 has a slot 66 therein and intermediate the prongs and the slot 66 the plate has an aperture 67 therein.

75 The shifting member 62 is positioned between

the shifting member 56 and the top of the casing 36.

The top of the casing 36 has an elongated slot 68 therein (see Figs. 10 and 11) which aligns with the apertures and slots in the plate portions of the shifting members.

On the top of the casing 36 I provide a shifting lever 69 for operating the shifting member 56 and a shifting lever 70 for operating the shifting member 62. The shifting lever 69 adjacent one 10 end thereof is pivotally secured to the casing 36 as at 71 and the opposite end has a handle member 72 thereon and adjacent the pivot 71 the lever 69 has an arcuate aperture 72' therein. The shifting lever 70 is positioned over the lever 69 15 and is pivotally secured thereto as indicated at 73.

A bolt 74 is positioned in the arcuate aperture 72' of the lever 69 and extends downward through the slot 68 in the casing 36 and the slot 66 in the shifting member 62 and threadedly engages the plate 51 of the shifting member 56.

Positioned in the aperture 67 of the shifting member 62 I provide a bolt 75 which extends upward through the slot 60 of the shifting member 56 and extends upward through the casing slot 68 and is positioned in an aperture 76 in the lever 70 and has lock nuts 78 thereon to retain it in position.

When the levers 69 and 70 are in the positions shown in Fig. 10 the gear 44 meshes with the gear 48 and when the shaft 39 is rotated the shaft 47 will be rotated in one direction.

When the lever 69 is moved in the direction indicated by the arrow in Fig. 10 to the position shown in Fig. 11 the gear 44 moves out of mesh with the gear 48 and the gear 45 moves into mesh with the gear 48 whereby upon rotation of the shaft 39 the shaft 47 will be rotated in the opposite direction.

Mounted on the bar 32 at the end thereof opposite the operating member 35 I provide an operating member 76' which is shown in detail in Fig. 6. As shown the operating member 76' includes a casing 77' which includes an apertured boss 78' (see Fig. 3) in which one of the reduced bar portions 33 of the bar 32 is positioned. The casing 77' is shown as secured in position on the bar by a set screw 79. A shaft 80 is rotatably mounted in the casing 77' and has a bevel gear 81 secured thereto which meshes with a bevel gear 82 secured to a shaft 83 which is rotatably mounted in the casing 77'. One end of the shaft 80 like the shaft 39 of the operating member 35 is positioned in the sleeve 41 and has a key member 80 thereon (see Fig. 3) which is positioned in 45 one of the slots 42 of the sleeve. The shaft 83 has an enlarged sleeve 84' thereon which is secured to the shaft 83 by a pin 85 one end of which projects beyond the side of the sleeve. An elongated hollow roller 86 is mounted on the sleeve 60 84' and adjacent one end has an enlarged recess 87 therein and a slot 88 opening into the recess. The roller 86 is positioned on the shaft 83 with the sleeve 84' positioned in the recess 87 and the pin 85 positioned in the slot 88. The edge of the 65 piece of canvas 53 opposite the edge thereof which is secured to the roller 50 is secured to the roller 86 by a plate 89 which is secured to the roller by screws 90. A portion of the canvas 53 is normally rolled around the roller 86.

At the foot, the frame includes cylindrical uprights 91 each of which is engaged by a clamp 92. This clamp includes a J-shaped member 93 and a clamping plate 9. (See Fig. 24.) Bolts 95 hold the clamping plate and stem of the J 75

against the foot posts 12 while the frame uprights 91 are held in the curve of the J as shown by a bolt 96. By loosening the bolts 95 and 96 the clamp may be shifted and the position of the fracture frame post 91 may be adjusted.

Positioned in each of the uprights 91 I provide a rack bar 97 having gear teeth 98 thereon. Positioned on one of the uprights 91 I provide an operating member 99 which is similar in all respects to the previously described operating member 26 except that the shaft 39 is of less length and the shaft 27 extends out of the casing and has a key member 100 thereon and is positioned in a sleeve 101 which has a slot 102 therein in which the key 100 is positioned. (See Fig. 2.) Mounted on the other upright 91 I provide an operating member 103 which is shown in detail in Fig. 15. The operating member 103 includes a casing 104 having a shaft 105 rotatably mounted therein on which a gear 106 is secured. Adjacent the gear 106 the casing 104 and the upright 91 have an aperture 107 therein in which the gear 106 is positioned to mesh with the gear teeth 98 of the rack bar 97. The shaft 105 extends towards the opposite side of the bed and has a key member 108 thereon and is positioned in the sleeve 101 with the key positioned in the slot 102 of the sleeve.

Each of the rack bars is provided with a hollow boss 109 on its upper end through which a shaft 110 extends. (See Fig. 2.) These shafts 110 are held in place by means of set screws 112 and the inner end of each shaft supports a boss 113 which is mounted on a fracture frame foot member 114. The foot member 114 extends from one boss 113 to the other across the foot of the bed and is provided with support bolts 115.

Adjacent each of the bosses 113 the foot member 114 has a hollow bearing member 116 thereon which is adapted to receive a reduced shaft portion 117 of the roller member 50 or 86. (See Figs. 2 and 5.)

When the rollers 50 and 86 are operatively mounted on the shafts 47 and 83 and in the bearings 116 and the lever 69 is in the position shown in Fig. 11 and the shaft 39 is rotated, both the rollers 50 and 86 will rotate in the same direction. When the lever 69 is in the position shown in Fig. 10 and the shaft 39 is rotated the rollers 50 and 86 will be rotated in opposite directions.

For applying traction to a patient's limb I provide a traction device 118 which is shown in detail in Figs. 16 and 17. As shown the traction device 118 includes an upright post 119 which is adapted to be removably secured to the foot bar 114 by a clamp member 120. The post 119 has a plurality of apertures 121 therein. Mounted on the post 119 I provide a slide member 122 which has a bolt 123 therein which is positioned in one of the post apertures 121 and has a wing nut 124 thereon. The slide member 122 includes a plate portion 125 which extends outward at a right angle to the post. Pivotally mounted on the plate 125 as by a bolt 126 I provide an arm 127. The arm 127 has a pin 128 thereon which is adapted to be positioned in one of a plurality of apertures 129 in the plate 125 and the bolt 126 has a wing nut 130 thereon for clamping the arm 127 in position. Depending from the arm 127 I provide a pulley 131 through which a cord 132 is roved. One end of the cord 132 is adapted to be secured to a cast on a patient's limb and the opposite end has a hooked member 133 thereon for supporting a weighted member 134.

Mounted on the device A I provide a frame 135

which includes a pair of spaced vertical head posts 136 and a pair of spaced vertical foot posts 137. Transversely the head posts 136 are connected by a rigid cross member 138 and the foot posts 137 are connected by a rigid cross member 139. Longitudinally the head and foot portions of the frame 135 are connected by two rods 140 which are secured to the head and foot portions by clamp members 141. One or more cross bars 142 may be secured to the bars 140 by adjustable clamp members 143 which slide on the bars 140 and various other devices may be suspended from the bars 140 such as the trapeze 144.

The foot posts 137 at their lower ends are formed forked as at 145 to fit over the bolts 115 on the foot bar 114 of the frame (see Fig. 2) and the head posts 136 at their lower ends are formed forked as at 146 to fit over bolts 147 provided on the operating devices 35 and 76.

In Figs. 18, 19, and 20 I have indicated modified canvas roll operating devices generally at 150 and 151. When the devices 150 and 151 are used two of the rack bars 97 and its associated parts are used at the head of the bed and two rack bars 97 are used at the foot of the bed.

The operating devices 150 and 151 each include a casing 152 having depending hollow bosses 153 (see Fig. 19) in which the rod 110 of the associated rack bar 97 is positioned. Rotatably mounted in the casing 152 of the device 150 I provide a shaft 154 the outer end of which includes a wrench or crank engaging portion 155. The opposite end of the shaft 154 is positioned in a sleeve 156 and has a key member 157 thereon which is positioned in a slot 158 in the sleeve. Secured to the shaft 154 within the casing I provide a bevel gear 159 which meshes with a bevel gear 160 secured to a shaft 161 which is rotatably mounted in the casing. The shaft 161 is an integral part of one wall of a housing 163. Extending from the said one wall of the housing 163 I provide a hub portion 161a and a reduced stud shaft 161b which extends out of the housing 163. Rotatably mounted on the hub portion 161a I provide a worm gear 162. The construction is such that the worm 165 together with the housing 163 walks about the shaft 161. Rotatably mounted in the housing 163 I provide a shaft 164 having a worm pinion 165 thereon which meshes with the worm gear 162. Each end of the shaft 164 projects out of the housing 163 and includes wrench or crank engaging portions 166. The gear 162 includes a sleeve portion 167 which extends out of the housing 163 and surrounds the stud shaft 161b. The sleeve 167 has a pin 168 projecting from one side thereof. The sleeve 167 is positioned in the roller 50 with the pin 168 positioned in the slot 52 as previously described in connection with the operating device 35.

Rotatably mounted in the casing 152 of the device 151 I provide a shaft 169 one end of which projects out of the casing and is positioned in the sleeve 156 and has a key member 170 thereon which is positioned in a slot 171 in the sleeve.

Within the casing the shaft 169 has a bevel gear 172 secured thereto which meshes with a bevel gear 173 secured to a shaft 174 which is rotatably mounted in the casing. The shaft 174 has a hub member 175 secured thereon and a sleeve member 176 loosely mounted thereon. The hub 175 has an aperture 177 therein and a bayonet slot 178 opening into the aperture 177. Positioned in the aperture 177 I provide a slide bar 179 having a screw 180 secured thereto and positioned in the bayonet slot 178.

- To operatively connect the hub 175 and the sleeve 176 the slide bar 179 is positioned in one of a plurality of apertures 181 provided in the sleeve member 176. The sleeve 176 has a pin 182 projecting from one side thereof. The shaft 174 is positioned in the canvas roller 86 with the sleeve 176 positioned in the roller recess 87 and the pin 182 positioned in the roller slot 88.
- In operation, when the hub 175 is operatively connected to the sleeve 176 by the slide bar 179 and the shaft 154 is rotated the gear 159, through the medium of the gear 160 and the shaft 161, will rotate the roller 50. At the same time the shaft 154 will rotate the shaft 169 through the medium of the sleeve 156, and the gear 172 will rotate the roller 86 through the medium of the shaft 174, hub 175, slide bar 179, and sleeve 176.
- To rotate the roller 50 independently of the roller 86 by means of the crank engaging portion 10 the slide bar 179 of the device 151 is moved out of the aperture in the sleeve 176 and the shaft 164 of the device 150 rotated whereupon the gear 159 will rotate the gears 160 which in turn will rotate the shaft 161 and thus rotate 15 the housing 163 and causing the sleeve 167 to rotate the roller 50, and although the shaft 154, the sleeve 156, and the shaft 174 will be rotated the roller 86 will not rotate. The construction shown in Figs. 18, 19 and 20 is employed when 20 the nurse wishes to change the canvas. In this case the patient is lowered until he rests upon the bed whereupon the operation just described is performed and the canvas is then unrolled freely from the rail 86 until the free end on this 25 roll is secured after which the entire canvas is slipped from under the patient and rolled upon the roll 50. A fresh canvas is then inserted under the patient and one end thereof is secured on the roll 50 and wound after which the other 30 end is wound onto the roll 86 after which the slide bar 179 is returned to position. An alternative way of rotating the roller 50 alone is to rotate the shaft 164 thereby rotating the worm pinion 165 which will rotate the worm gear 162 35 thereby rotating the sleeve 167 which in turn rotates the roller 50. When the shaft 164 is rotated the housing 163 remains stationary and the gear 162 and the sleeve 167 rotate freely about the stud shaft 161b.
- In Figs. 21 and 22 I have indicated a simplified form of canvas roller operating device generally at 185. When the device 185 is used two rack bars 97 and their associated parts are used at the head of the bed and also at the foot thereof. The device 185 includes a transverse bar 186 having a depending hollow boss member 187 adjacent each end in which the bars 110 of the rack bars 97 are positioned. Adjacent each end of the bar 186 a shaft 188 is rotatably mounted thereon 40 in which is secured a pinion gear 189 and a sleeve 190 which is secured to the shaft by a pin 191 which projects from one side of the sleeve. To prevent inward rotation of the gears 189 I provide adjacent each of the gears a dog member 45 192 which is pivotally secured to the bar 186 as at 193.

To rotate the gears 189 a spanner wrench 194 is applied to the gear teeth. The previously described canvas rollers are adapted to be operatively mounted on the shafts 188 by positioning the shafts 188 in the rollers and the sleeves 190 in the end recesses of the rollers with the pins 191 in the roller slots.

Having thus described my invention I claim:

1. In a reversing mechanism for operating the rolls of an invalid's bed, a shaft having a bevel gear thereon, a second shaft at right angles to the first shaft, a pair of gears on the second shaft and arranged on opposite sides of the first gear, said pair of gears being splined on their shaft to move towards and from the first gear, a support, a shifting member movably mounted on said support and engaging one of said pair of gears, a second shifting member movably mounted on said support and engaging the other of said pair of gears, a lever pivoted on said support, a cam 10 on said lever, said support having a slot, means on said first mentioned shifting member passing through said slot and engaging said cam to shift said first mentioned shifting member, a pin on said second shifting member passing through 15 said slot, a second lever engaging said pin and pivotally mounted on the first lever, the pivot of said second lever being disposed at one side of the axis of said first lever whereby when the first lever has moved said first shifting member to 20 withdraw its associated gear from said first gear said other of the pair of gears will be moved into engagement with said first gear.
2. In a reversing mechanism for operating the rolls of an invalid's bed, a shaft having a bevel gear thereon, a second shaft at right angles to the first shaft, a pair of gears on the second shaft and arranged on opposite sides of the first gear, said pair of gears being splined on their shaft to move towards and from the first gear, 25 a housing on said driven shaft, a shifting member movably mounted on said housing and having a fork engaging one of said pair of gears, a second shifting member movably mounted on said housing and having a fork engaging the other of said pair of gears, said housing having a slot, a lever pivoted on said housing, a cam slot 30 on said lever, a pin on said first mentioned shifting member and passing through said slot, said cam slot receiving said pin and being so constructed that when said lever is shifted said first mentioned shifting member is moved, a second pin on said second shifting member passing through said slot, a second lever engaging said second pin and pivotally mounted on the first lever, the pivot of said second lever being disposed at one side of the axis of said first lever whereby when the first lever has moved said first shifting member to withdraw its associated gear from said first gear said other of the pair of gears will be moved into engagement with said first gear.
